SLEEPING PAD

Charles D. Karr, Holland, Mich.

Application March 30, 1934, Serial No. 718,135

2 Claims. (Cl. 5—355)

The invention relates to pads especially adapted to be placed upon a spring mattress, taking the place of an attached padding therefor.

The objects of the invention are to simplify
5 and generally improve the construction of such
pads, and to provide a pad the opposite sides of
which will differ in warmth. Other objects will
be apparent from the appended description of
the pad.

10 In the accompanying drawing—

Fig. 1 is a perspective view, partly in section, of the pad in course of manufacture; and

Fig. 2 is a sectional detail showing the inner section of the pad and a tie cord looped therethrough.

15 The improved pad is composed of three separate layers, the central layer 10 being preferably a compressed bat of fibrous material, such as cotton, wool, or commercial curled hair, and the 20 outer layers 11, 12, being in the form of quilts filled with similar material. The outer facing of each of the quilts should be of stout material, such as ticking. Its inner facing may be of lighter material, such as muslin.

25 Each of the quilts is stitched through at frequent intervals, as indicated at 13. These seams are preferably formed under light tension, and do not materially lessen the pliability of the quilt. The two quilts are secured together by means
30 of stout threads or cords 14. Preliminary to the assembling of the several sections of the pad these cords may be stitched through the middle section 10, that loose ends may be available at each side of the bat.

35 As I am now practicing the invention one of the quilts is applied to the face of the inner bat and secured thereto by means of the cord ends 14, stitched through its inner facing and tied. The companion quilt is similarly secured, the cords
40 14 being in this instance drawn somewhat tightly through the middle section of the pad and, after being stitched to the inner facing of the quilt, are knotted for secure attachment. The cords 14 may be as numerous as the judgment
45 of the manufacturer may dictate. I have found that they may be few in number, and need not be disposed systematically. The procedure in se-

curing the outer quilts together by means of cords passing through the middle element may vary.

As indicated at Fig. 1, the cords 14 have been first looped through the inner face of the lower quilt and then passed through the inner element and their ends left free to be engaged (one or both of them) with the inner facing of the upper quilt by means of a needle and then tied together.

As suggested in Fig. 2, both ends of the cord 10 may be first passed through the inner bat, leaving a loop on one side thereof, the loose ends being then secured to the inner facing of a quilt, the loop at the opposite side of the pad may be 15 cut and the separated ends similarly secured to the inner facing of the other quilt.

The pad is provided with a marginal boxing 15, of stout material, such as ticking, stitched to the margins of the quilts, the attaching seams being preferably bound by tape, as indicated at 16.

One of the quilts, as 12, is preferably filled with wool, and the other, 11, with commercial curled hair, thereby providing facings differing in warmth.

The details of construction may be varied within the scope of the appended claims. 25

I claim as my invention—

1. A sleeping pad comprising an inner bat of fibrous material, a quilt formed of a bat of fibrous material enclosed between fabric sheets engaged directly with the fibrous material on each opposite face of the inner bat, and means securing the quilts to the inner bat comprising cords attached to the inner fabric sheets of the quilts and penetrating the inner bat of the pad. 25

2. A sleeping pad comprising an inner bat of fibrous material, a quilt formed of a bat of fibrous material enclosed between fabric sheets engaged directly with the fibrous material on each opposite face of the inner bat, and means securing the quilts to the inner bat comprising cords attached to the inner fabric sheets of the quilts and penetrating the inner bat of the pad, in combination with a fabric boxing covering the sides of the pad and secured to the margin of the quilts. 40
